[57] CLAIM

The ornamental design for the vacuum seal cracking tool for jars, as shown and described.

DESCRIPTION

FIG. 1 is a top plan view of a vacuum seal cracking tool for jars showing our new design;

FIG. 2 is a side elevational view thereof;

FIG. 3 is a bottom plan view thereof;

FIG. 4 is a sectional view taken along line 4—4 of FIG. 3;

FIG. 5 is a sectional view taken along line 5—5 of FIG. 3;

FIG. 6 is a top plan view of an alternate embodiment of FIG. 1;

FIG. 7 is a side elevational view of FIG. 6;

FIG. 8 is a bottom plan view of FIG. 6;

FIG. 9 is a sectional view taken along line 9—9 of FIG. 8; and,

FIG. 10 is a sectional view taken along line 10—10 of FIG. 8.
